UNITED STATES PATENT OFFICE.

CLARK H. HODGE AND ARTHUR F. SCHULTZ, OF SOUTHGATE, CALIFORNIA.

DESIGN FOR AN ORNAMENT FOR AUTOMOBILE RADIATORS.

Application filed April 14, 1927. Serial No. 21,602. Term of patent 14 years.

To all whom it may concern:

Be it known that we, CLARK H. HODGE, and ARTHUR F. SCHULTZ, both citizens of the United States, and residents of Southgate, in the county of Los Angeles and State of California, have invented a new, original, and ornamental Design for Ornament for Automobile Radiators, of which the following is a specification, reference being had to the accompanying drawings, forming part thereof.

Figure 1 is a perspective view taken from the front of our ornament,

Figure 2 is a perspective view taken from the rear and to one side of the ornament, and

Figure 3 is a substantially diagrammatic side view of our ornament as shown in Figure 1.

We claim:—

The ornamental design for an ornament for automobile radiator, as shown.

CLARK H. HODGE.
ARTHUR F. SCHULTZ.
